POWDER CONTAINER

Enar Anderson, North Attleboro, Mass.

Application November 19, 1940, Serial No. 366,294

8 Claims. (Cl. 132—82)

The invention relates particularly to boxes for carrying loose powder.

It has become customary for ladies to carry loose powder boxes in their handbags, etc. The powder boxes may be carried in the well or other parts of the bag where they may come into more or less direct contact with other articles carried by the user. It is necessary, in order to have a satisfactory powder box, to provide means for preventing spilling or leakage of the loose powder into the handbag, since powder will cling to and soil articles with which it comes in contact.

It is customary to provide a powder pad, or puff in the box to be used in applying the powder, and there is also usually provided a sifter or foraminous cover to aid in control of the amount of loose powder collected by the pad or puff in using. The use of these various articles inside of the box reduces the amount of powder which may be placed therein to a small quantity, and if leakage from the box is great sufficient quantities of powder may escape from the box either when it is opened, or when the box is closed to make the use of the box impractical. It is an object of the present invention to provide a container for powder providing a secure seal against leakage while not interfering with the availability of the powder to the user and enabling a sufficient quantity of powder to be carried in the container.

For this purpose there is provided a box having a cover portion and a bottom portion. About the edges of the bottom of the box there may be placed or fastened by any suitable means a border of villous material, which may have a nap, being somewhat compressible, felt being suitable. The border may be of any suitable width. The depth of the border is not of material importance but preferably it will be deep or thick enough to provide a well which will contain a sufficient quantity of powder to supply the user for a reasonable period of time. The border will be placed in the bottom of the box so as to leave exposed a villous side to form the top surface of the border.

There will also be provided in the box a sifter composed of a sheet of any foraminous material. The sifter may be provided with a frame, or edge, of felted or villous material placed on the side of the sifter adapted to come in contact with the border in the bottom of the box. The sifter may be of sufficient size to overlie the border in the bottom of the box. Thus when the powder is in the container, and the sifter is in place, contact of the villous surfaces of the border and sifter will tend to form the two materials into a powder

impermeable edge and this effect may be enhanced when they are pressed closely together.

Over the sifter there will be provided in the box a powder applicator or pad which may be of compressible material or construction. The combined depth or thickness of the border, sifter and powder pad may be greater than the depth of the container so that when the box is closed there may be a close, tight compression of the various articles in the box to cause the powder to remain in place, and the edges of the border and of the sifter to remain sealed while the pad seals the sifter against passage of powder.

The container may be of any desired shape or form, but is shown in the accompanying drawing as oblong for purposes of illustration.

Figure 1 is a perspective view of a powder box in open position with a border in position in its bottom. Fig. 2 is a perspective view of a sifter. Fig. 3 is a perspective view of a pad. Fig. 4 is a fragmentary vertical section on an enlarged scale through a side of the box in open position with sifter and applicator in place. Fig. 5 is a fragmentary vertical section similar to Fig. 4 and showing the cover in closed position.

A powder box may have a cover 10 and a hollow bottom member 11. About the inside of the bottom plate of the member 11 is shown a border 12. The border 12 may be attached to the bottom member 11 in any suitable way, as by an adhesive, or may be placed in the bottom member 11 without being attached thereto. When the border 12 is in position in the bottom member 11 there is formed a well 13 to receive and store loose powder. This border 12 will be of some suitable material which may be compressible or villous or both. For this purpose felt may be desirable. A sifter 14 of foraminous material is attached to a frame, border or edge 15 of villous material such as felt for instance. The frame 15 of the sifter may be sufficiently large to rest on the border 12 throughout its periphery. There is shown an applicator 16 adapted to be placed in the bottom member 11 over the sifter 14. The applicator will preferably be of compressible material or construction and may be sufficiently large to cover the entire opening in the sifter and to rest on or overlie the border 12 throughout its periphery.

When the border 12 and the sifter 14 and the pad 16 are in position in the receptacle the border 12 and the frame 15 of the sifter 14 will be in close contact and upon them will rest the applicator 16. The thickness of the assembled parts is greater than the depth of the box.

Protection against escape of the powder is insured when the box is closed. Closure of the cover will put pressure on the assembly and compress the felt members or force them into close contact which may be accomplished by pressure on the applicator which may be at the same time compressed. Thus powder in the well 13 will be sealed against escape at the edges of the well by the contact of the villous materials of which the borders 12 and 15 are made and from escape through the foraminous portion of the sifter 14 by the pressure of the applicator 16.

As illustrated in Fig. 4 a projection 17 on the inside of the cover 10 may be provided to press down upon the applicator 16. The projection 17 is preferably large enough to overlie somewhat the frame 15. Thus the pressure of the projection 17 will press tightly together the applicator 16, the sifter 14 and the border 12 to form a close seal against leakage of powder when the box is closed. The borders 12 and 15 being of villous or nap material will be compressed somewhat by the pressure of the cover with or without the projection 17 and may tend to remain in close contact even when the pressure is removed by the opening of the cover 10.

Changes in sizes, materials, shapes and arrangements may be made without departing from the invention as set out in the appended claims.

I claim as my invention:

1. In a powder container having a cover; a felt border on the bottom of the container within which powder may be placed; a felt frame about the size of the border; a foraminous sheet covering the frame and attached to it at its edges, the frame being adapted to overlie the border so that the powder may sift through the foraminous sheet; and a compressible powder applicator of substantially the same size as the frame, the combined thickness of applicator, frame, foraminous sheet and border being greater than the inside depth of the container so that when the cover is closed it causes the border and frame to form a tight seal for the powder and the applicator to prevent powder passing through the foraminous sheet.

2. In a powder container having a cover, a felt border on the bottom of the container to form a well within which powder may be placed, a foraminous sheet having a felt frame adapted to overlie the border, and a compressible powder applicator of substantially the same size as the frame adapted to be placed over the foraminous sheet so that when the cover is closed the border, frame and applicator form a tight seal for the powder.

3. In a powder receptacle having a cover, a

layer of compressible material about the periphery of the inside of the bottom of the receptacle providing a space to store powder, a sifter having edges lying on the compressible layer, and a pad 5 the edges of which overlie the edges of the sifter, the cover when closed causing the assembly to seal the powder against escape.

4. In a powder container; a felt border on the bottom of the container within which powder 10 may be placed; a felt frame about the size of the border; a foraminous sheet covering the frame 15 and attached to it at its edges, the frame being adapted to overlie the border so that powder may sift through the foraminous sheet; a compressible powder applicator of substantially the same size as the frame; a hinged cover for the container, and a projection on the inside of the cover as large as the frame adapted to press on the applicator 20 when the cover is closed so as to cause the border and frame to form a tight seal for the powder and the applicator to prevent powder passing through the foraminous sheet.

5. In a powder receptacle having a cover, a layer of compressible material fastened about the 25 periphery of the inside of the bottom of the receptacle providing a space to store powder, a sifter having edges lying on the compressible layer, and a powder pad fitting the container 30 and the cover so as to cause the assembly to seal the powder against escape when the receptacle is closed.

6. In a powder receptacle having a cover, a layer of compressible material about the periphery of the inside of the bottom of the receptacle 35 providing a space to store powder, a sifter having edges lying on the compressible layer, and a pad the edges of which overlie the edges of the sifter, the cover when closed causing the edges of the sifter to form a powder seal with the compressible 40 material and the pad to form a powder seal with the sifter.

7. In a powder receptacle having a cover, a layer of villous material forming a border about the periphery of the inside of the bottom of the 45 receptacle to provide space to store powder, a sifter having villous edges lying on the villous border, and a pad the edges of which overlie the edges of the sifter.

8. In a powder receptacle having a cover, a border of compressible material about the bottom 50 of the container within which powder may be placed, a sifter having a frame of compressible material, and a compressible pad thick enough to form with the border and sifter a tight seal when the receptacle is closed.

ENAR ANDERSON.
